SHARPENING DEVICE FOR CUTLERY

Robert J. Foster, Pontiac, Mich.

Application February 21, 1944, Serial No. 523,279

6 Claims. (Cl. 76—82.2)

The present invention relates to scissors sharpeners, and more particularly, to a support therefor.

The primary object of the invention is to provide a scissors sharpener in which the blade of the scissors is held in such a manner as to assume its normal bow so that as the blade is sharpened it will be sharpened in a bowed condition in lieu of the present practice of sharpening the blade while the same is held relatively straight.

Another object of the invention is to provide a device for sharpening scissors to facilitate the corrugating of the blade lengthwise of the cutting edge which is highly desirable in various types of scissors and shears to increase the cutting action.

Another object of the invention is to provide a scissors sharpener having a guide means for supporting the free end of a file or other sharpening tool at the required angle relative to the blade of the scissors so that the cutting edge of the scissors may be sharpened at an oblique angle initially and the file or cutting tool adjusted to a smaller angle so that another surface may be formed on the cutting edge and thereby provide a longitudinal ridge or corrugation on the scissors blades in addition to the initial bevelled or oblique surface.

Another object of the invention is to provide a scissors sharpening device having concave and convex anvils disposed in close relation one to the other so that the blades may be laid on the convex anvil and tapped slightly to impart the required bow thereto while the handles of the scissors may be supported on the convex anvil and tapped with an instrument to give the required and necessary pitch thereto.

Another object of the invention is to provide a scissors sharpener and a support therefor which may be used in tonsorial parlors and dressmaking shops and in which the support may be placed on the seat of a chair so that the operator may assume a sitting position thereon while sharpening the scissors.

Another object of the invention is to provide a device of the above-mentioned character which may be adjusted angularly relative to the support so that the operator can manipulate the sharpening tool at the required oblique angle relative to the direction of movement of the file or other sharpening tool.

Another object of the invention is to provide a scissors sharpener in which the blade clamping and supporting means is offset laterally from the file guide and support means to facilitate the

movement of the file in such a direction as to provide a saw-toothed profile along the cutting edge of the blade.

Other objects and advantages of the device will become apparent during the courses of the following description of the accompanying drawings, wherein:

Figure 1 is a top plan view of the scissors sharpener showing the manner in which the scissors 10 are supported so that one of the blades may be held in a slightly bowed position during the sharpening thereof;

Figure 2 is a front elevational view of the scissors sharpening device further showing the manner in which the file is supported on a compound angle relative to the blade;

Figure 3 is an end elevational view of the scissors sharpening device illustrating the general arrangement thereof and the location of the 20 convex and concave anvils at one side thereof;

Figure 4 is a vertical cross-sectional view taken on line 4—4 in Figure 2 looking in the direction of the arrows and illustrating the manner in which the handle portion of the scissors is 25 clamped so that the blade will project therefrom and be engaged by a support for imparting the required bow thereto;

Figure 5 is a top plan view of a guide attachment adapted to be affixed to the end of the file 30 or other sharpening instrument; and

Figure 6 is a side elevational view of the guide attachment illustrating the manner in which the same is secured and attached to the end of the file.

Figure 7 is an end elevational view of the scissors sharpener showing its attachment to a seat board.

In the drawings wherein for the purpose of illustrating the invention like reference characters will be employed to designate like parts throughout, the reference character 5 will generally be employed to indicate a base having a top surface 6 and marginal depending flange portion 7. The base 5 is preferably formed rectangular in shape and adjacent one corner thereof is located a vertical support 8 terminating in a jaw portion 9 having an oblique jaw surface 10. The upright 8 is spaced from the top wall 6 of the base by means of a connecting web portion 11 to reinforce the upright 8 and prevent vibration thereof. The upright 8 is provided with a rounded socket surface 13 for receiving the rounded end portion 14 of a movable jaw member 15. The jaw member 15 is disposed in opposed relation to 55 the jaw member 9 and is provided with a com-

plementary jaw surface 16 substantially parallel with the oblique jaw surface 10. The movable jaw member 15 is provided with an opening 17 for receiving a clamping bolt as at 18 with its threaded end received in a threaded bore in the jaw member 9 and its opposite end provided with a head 19 having opposed thumb pieces 20.

Formed integral with the base top wall 6 and intermediate the ends thereof in spaced relation from the upright 8 is a blade support 21 reenforced from the top wall 6 by a thin interconnecting web portion 22 so as to brace the upright 21 in a manner similar to the upright 9. The extreme upper end of the upright 21 is notched as at 23 for receiving the tip or end of the scissors blade as indicated in Figures 1 to 4 inclusive.

The scissors sharpened are of the usual type and include cross blades 25, pivoted as at 26 and having handle portions 27 for the respective blades. As shown in Figure 2, the handle portion 27 of the scissors is gripped between the oblique jaw surfaces 10 and 16 of the jaws 19 and 15 so that the free end of the blade 25 will be received in the notch 23 of the support 21. When the scissors are thus arranged with one of the blades positioned as above, the clamping bolt 18 is tightened to move the jaw 15 toward the jaw 9. By reason of the oblique relation of the jaw surfaces 10 and 16, a slight bulge is imparted to the blade 25 which is slightly accentuated over the normal bow inherent in most all scissors and shears. The scissors are now in position to be sharpened by a file or the like as at F and in order to guide the file F along the surface of the cutting edge, guide means is provided on the other side of the base 6 and comprises a pair of spaced uprights 28 and 29 as shown clearly in Figure 1 formed integral with the top wall of the base 6 and reinforced therefrom by triangular-shaped reenforcing web portions 30 and 31 respectively. The uprights 28 and 29 are provided with a series of spaced supporting rods 32 one end of which is threaded for reception in spaced threaded openings 33 in the upright 28 while the other end extends through an opening in the upright 29 in alignment with the corresponding threaded opening or bore 33. The ends of the rods 32 are provided with tool-receiving heads 35 which permit the rods to be tightened in place by means of a screw-driver or the like. It is noted that the file guiding and supporting rods 32 are offset longitudinally from the scissors support to facilitate the correct angular movement of the file F during the sharpening of the blade 25.

The supporting rods 32 are adapted to slidably engage an attachment 36 secured to the end of the file F and said attachment is provided with a head 37 slotted as at 38 to provide a pair of jaw portions 39 so as to grip the end of the file F. A clamping screw 40 is passed through the head 37 so as to draw the clamping jaw 39 together and, if desired, the complementary faces of the clamping jaws 39 may be cut away to conform to the contour or shape of the file end.

Formed in another corner of the base 5 on the top wall 6 thereof is a pair of anvil blocks 42 and 43 disposed in side by side relation and it is noted that the anvil block 42 is provided with a convex surface 44 while the anvil block 43 is provided with a concave surface 45.

The file F is provided with a handle H to be grasped by the operator during the sharpening of the scissors. If desired, various types of files may be used during the sharpening operation but in accordance with the best practice, a cross cut

file is used first with the slide rod 36 supported on the lowermost rod 32 so as to form a cutting surface along the edge of the blade 25 after which a single cut file is used with the slide rod 36 supported on one of the uppermost guide rods 32 so as to impart a slight saw-toothed surface to the cutting edge on an angle different than the first surface sharpened, which is highly desirable in various types of shears and particularly, barber's shears so as to prevent the pair from slipping along the blade during the shearing action thereof.

As shown in Figure 7, the base 5 is supported on a seat board 46 which may be tapered at one end as at 47 to permit the end of the board to be placed upon the seat of a chair so that the operator may assume a sitting position thereon with the other end of the board 48 projecting in front of the operator. The base 5 is pivoted to the end of the board 48 by means of a bolt 49 extending through a central opening 50 in said base having a surrounding boss 51 to provide a bearing surface for engaging the board. The bolt 49 may be held in place by means of a nut or the like as at 52 threaded on the lower end thereof.

In operation, the scissors are clamped in position between the jaws 9 and 15 as shown in Figures 1 and 2 so that the free end of the blade 25 of the scissors will engage and be received in a slot 23 in the upper end of the upright 21. With the scissors in this position, and the blade substantially horizontal the file F is presented to the blade with the slide attachment 36 resting on one of the lowermost rods 32 so that a reciprocatory motion applied to the file F will impart an annular contour or surface on the cutting edge of the blade 25. After the blade has thus been sharpened with a cross-cut file, a single cut file may be substituted and the guide rod portion 36 of the attachment 37 may be supported on one of the uppermost rods 32 so that a to and fro movement applied to the file with the file on the compound angle will impart another surface to the cutting edge and provide the same with a longitudinal rib or corrugation extending lengthwise of the cutting edge. The last-mentioned surface will be cut with a minute saw-toothed edge which, as mentioned before, is highly desirable.

If it is desired to bow the blade 25 of the scissors beyond the normal bow, the blade is laid on the anvil 43 and struck a blow with a hammer or the like so as to bend the blade to the proper shape. If it is desired to change the pitch of the handles 27 they are placed on the anvil 44 and struck with a hammer or the like so as to bend the handles to such a position as to follow in a straight line plane relative one to the other.

Obviously, the scissors blade 25 may be sharpened to provide the cutting edge with various angular surfaces by simply moving the guide portion of the attachment into sliding engagement with the various horizontal slide guide rods 32.

It is to be understood that the form of the invention herewith shown and described is to be taken as a preferred embodiment of the same and that various changes may be made in the shape, size and arrangement of parts without departing from the spirit of the invention or the scope of the subjoined claims.

What I claim is:

1. A scissors sharpener comprising a base, a pair of spaced uprights on the base for supporting a pair of shears to be sharpened and a guide member disposed at the opposite side of the base for guiding a sharpening tool with respect to one

of the blades of said shears, said guide member consisting of a series of horizontal rods arranged for receiving and guiding the end of a sharpening tool disposed at various angles with respect to the blade of said pair of shears being sharpened.

2. A device for sharpening articles of cutlery, comprising a base, a support on the base adapted to clampingly receive an article of cutlery, an upright formed on the base in spaced apart relation from said support for engaging the end of said article of cutlery and imparting thereto a slight bow throughout its length, and a guide member disposed on said base in opposed relation to said support and upright for guiding a sharpening tool over the edge of said article of cutlery at a predetermined angle, said guide member consisting of a pair of spaced uprights at each end of the base having interconnecting guide rods extending therebetween.

3. A scissors sharpener comprising a base, a pair of spaced uprights on the base for supporting a pair of shears to be sharpened, and a guide member disposed at the opposite side of the base for guiding a sharpening tool with respect to one of the blades of said shears, said guide member consisting of a pair of spaced uprights at each end of the base having interconnecting guide rods extending therebetween.

4. A device for sharpening cutlery comprising a base, a pair of spaced uprights on said base, one of said uprights being provided with an obliquely arranged clamping jaw surface, a clamping jaw member for said one upright having a jaw surface complementary to said first-mentioned jaw surface for supporting and clamping an article of cutlery therebetween with the free end of said article engaging said other upright, whereby said article of cutlery will be bowed throughout its length, guide mechanism on said base for guiding a sharpening instrument along the cutting edge of said article of cutlery, and a clamping member for holding said clamping jaws in clamping engagement with said article of cutlery, said guide mechanism comprising a series of spaced rods and a guide extension affixed to the sharpening instrument for slidably engaging said rods and maintaining the instrument in a predetermined angle while in engagement with the article of cutlery.

5. A device for sharpening cutlery comprising

a base, a pair of spaced uprights on said base, one of said uprights being provided with an obliquely arranged clamping jaw surface extending at an angle to the longitudinal edge of said base, a clamping jaw member for said one upright having a jaw surface complementary to said first-mentioned jaw surface for supporting and clamping an article of cutlery therebetween with the free end of said article engaging said other upright, whereby said article of cutlery will be bowed throughout its length upon different arcs when various clamping pressures are exerted on said jaw surfaces, guide mechanism on said base for guiding a sharpening instrument along the cutting edge of said article of cutlery, a clamping member for holding said clamping jaws in clamping engagement with said article of cutlery, a pair of uprights on the base on the opposite edge thereof, a series of spaced rods extending between said uprights, and a guide extension affixed to the sharpening instrument for engaging said rods to position said instrument in a predetermined angle while in engagement with the article of cutlery.

6. A device for sharpening cutlery comprising a base, a pair of spaced uprights on said base, one of said uprights being provided with an obliquely arranged clamping jaw surface extending at an angle to the edge of the base, a clamping jaw member for said one upright having an inclined jaw surface complementary to said first-mentioned jaw surface for supporting and clamping an article of cutlery therebetween with the free end of said article of cutlery engaging said other upright whereby said article will be bowed throughout its length upon different arcs when the pressure between said jaws is varied, guide mechanism on said base for guiding a sharpening instrument along the cutting edge of said article of cutlery, a pair of uprights in opposed relation to said first-mentioned uprights, horizontal guide rods extending between said uprights, and a clamping member for holding said clamping jaws in clamping engagement with said article of cutlery, said guide mechanism comprising an extension affixed to the sharpening instrument having a rod portion for slidably engaging one of said horizontal rods disposed on the other side of the base.

ROBERT J. FOSTER.
